CLAIM

The ornamental design for a cup base illuminating floating ball, as shown and described.

DESCRIPTION

FIG. 1 is a perspective view of the cup base illuminating floating ball region showing our new design, wherein the cup base illuminating floating ball is in an illuminating state; FIG. 2 is a top view of cup base illuminating floating ball thereof;

FIG. 3 is a front view of the cup base illuminating floating ball thereof

FIG. 4 is a perspective view of the cup base illuminating floating ball region showing our new design, wherein the cup base illuminating floating ball is in a non illuminating state; FIG. 5 is a top view of the cup base illuminating floating ball thereof; and,

FIG. 6 is a front view of the cup base illuminating floating ball thereof.

All broken lines are directed to environment and are for illustrative purposes only. None of the broken lines form a part of the claimed design. The radiating lines in FIGS. 1-3 indicate illumination. The dark shading in FIGS. 4-6 compared to the same region shown unshaded in FIGS. 1-3 indicates a contrast in appearance between unlit and lit regions, and does not depict any particular color, texture, or material.
